SOUNDING-LINE FOR AIRCRAFT

Filed April 16, 1920

Inventor
Henry E. Krammer
By his. Attorney
Warren S. Orton.

UNITED STATES PATENT OFFICE.

HENRY E. KRAMMER, OF NEW YORK, N. Y.

SOUNDING LINE FOR AIRCRAFT.

Application filed April 16, 1920. Serial No. 374,268.

The invention relates in general to a lead line device for ascertaining and measuring vertical distances and specifically relates to such a device designed to be carried on an aeroplane or similar vehicle for the purpose of making soundings to ascertain how far the aeroplane is above the ground or water over which it is flying.

In such devices heretofore used on ships for making soundings the bob or other weight on the end of a flexible cable has been permitted to fall slowly by gravity until it strikes bottom. However, it is obvious that should such a device be utilized on an aeroplane, frequently moving at extremely high speeds, the drag of the bob while it is passing vertically at relatively slow speed through the air would introduce material errors in the indicated reading on the indicator's registering the amount of played out cable. This would obviously result in serious consequences to the machine especially when flying at high speeds and low altitude.

Accordingly, one of the objects of the invention is to provide a lead line device which is shot at high velocity downwardly from the machine so as to minimize the time element of transit and thus tend, as far as possible, to cause the cable to register the shortest line between the aeroplane and the ground or water over which it is flying.

I attain this invention broadly by positioning the bob defining the end of the cable within a downwardly pointing gun so arranged that the firing of the gun will forcibly project the bob which thus constitutes a projectile and cause the projected bob to draw with it the cable, unwinding from a freely turning reel and indicating the length of drawn off cable on a suitable indicator.

Still featuring accuracy in measurements, another object of the invention is to provide a simple form of automatically actuating signalling device which will promptly indicate to the operator the instant that the falling bob has struck an obstacle.

It can readily be appreciated that it is objectionable, if not dangerous, to have a cable from the aeroplane dragging on the ground even for a short period of time, and accordingly another object of the invention is to provide a means for quickly rewinding the cable onto the carrying reel which rewinding movement will be inaugurated instantaneously by the contacting of the bob with

Still another object of the invention is to provide means for automatically disconnecting the winding means from the reel when the bob has reached its fully raised position and for resetting the parts automatically in position for a quick succeeding sounding.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

The figure is a single sectional view taken through an aeroplane structure and through a preferred embodiment of my invention with certain parts shown in elevation and with the electric conductors shown diagrammatically.

In the following description and in the claims, parts will be identified by specific names for convenience of expression but they are intended to be as generic in their application to similar parts as the art will permit.

There is shown an aeroplane structure of a type such as is more fully disclosed in my copending application, Serial No. 243,564, filed July 6, 1918. A gun 11 constitutes a part of the aeroplane structure and includes a vertically disposed projectile guiding tube 12, into the upper end of which is telescoped an explosive chamber 13. The lower end of the chamber 13 is formed slightly conical to receive the conical head 14 of a bob or projectile 15 which is attached to the free end of a cable 16. The cable is passed through a stuffing box 17 defining the upper end of the chamber 13 and is coiled about a horizontally disposed take up reel 18. The gun is featured by a relatively long barrel and is directed either straight downwardly or preferably is inclined at a slight angle forwardly so as to compensate, at least to some extent, for the air resistance introduced by the forward drift of the machine during the two or three seconds that the projectile is in the air. The gun is loaded with an explosive charge intro-

duced into the charging port 19 and is fired by some conventional form of firing mechanism, such as the spark plug 20. The reel is supported in upstanding bearings 21 and 22 forming part of the aeroplane structure and includes a hub 23 provided with side flanges 24 between which is positioned the wound up portion of the cable 16. A portion of the hub is hollow and into the hollow portion is telescoped a shaft sleeve 25 fixed in the bearings 21 by means of the nut 26.

The cable is wound on the reel by means of an electric motor 27 which acts through a one-way clutch 28 and squared shaft 29 inserted in the adjacent end of the hub 23. The teeth 30 of the one-way clutch are arranged so that the reel in unwinding can turn freely without the load of the dead motor and so disposed that when the motor 20 is energized it will promptly pick up the reel and turn it in the direction to wind the cable thereon. The free end of the armature shaft is provided with a squared head 31 designed to be engaged by a hand crank 25 32, shown in dotted outline, so that the cable may be wound on the reel manually in case the electrical features of the disclosure become inoperative for any reason.

An odometer 33, or other measuring instrument is positioned on the bearing 22 and is operatively connected to the reel by a meshed geared connection 34. The odometer is so organized that the played out length of the cable is indicated in feet or 35 other linear units of measurement.

There are disclosed two electric circuits so connected that the movement of the projectile out of the gun closes one circuit and the contacting of the bob with the obstacle below 40 the machine will close another circuit and the succeeding coaction of these two circuit closers will cause the motor to become active.

Referring first to the elements which go to make up a circuit, hereinafter identified as 45 a motor circuit, there is shown a source of electric energy 35 one side of which is grounded by means of the conductor 36 on the frame of the machine. The other side leads by means of the conductors 37 and 38 to one end of a pivoted switch 39, which switch constitutes the armature of 50 an electromagnet 40 hereinafter more fully described. The movement of the switch into circuit closing position is under the influence of the electromagnet which effects a 55 closing of the circuit through a contact 41 and conductor 42 to one side of the motor 27. The other side of the motor is grounded on the machine by means of the conductor 60 43. The switch 39 is provided with a finger 44 which projects through the side of the gun and into the path of the bob 14.

By this construction it is understood that the presence of the bob in the gun maintains 65 the motor circuit opened so that the motor

is inactive as long as the bob is in its elevated position. A spring pressed stop button 45 is positioned in the path of the switch 39 and provides a resistance to any accidental movement of the switch. The stop however is sufficiently weak to permit the switch to be positively pushed away from the electromagnet and into a circuit breaking position by the action of the bob on the finger 44 and to permit the electromagnet to draw the switch into its circuit closing position in which position it is held by the button 45.

The second circuit, hereinafter identified as the control circuit, includes a conductor 46 which leads off from the conductor 37 to one side of the electromagnet 40, a conductor 47 which leads from the other side of the electromagnet to a signalling device 48, herein shown to be an electric light bulb, and from the electric light bulb through a conductor 48^a, and through the shaft sleeve 25 to the relatively stationary elements 49 of a rotary commutator 50.

The cable is provided with two conductors, one of which 51 has one end connected to the rotary element 50 of the commutator and the other conductor 52 which is grounded on the hub of the reel. The opposite or lower ends of the conductors 51 and 52 pass through the bob 14, as shown in dotted lines, and terminate in depending contact points 53 and 54. The circuit is closed through these points by means of a horizontally disposed contact plate 55 which is held in position spaced below the contact points by means of the coil spring 56.

The lower end of the explosive chamber 13 is defined by a stop ring 57 designed to have its lower side engaged by a stop plate 58 and having a resilient connection with the bob through the interposed spring 59 so arranged that the bob is cushioned in moving into its elevated position shown in the drawings.

In operation and assuming that the parts are in the position shown in the drawing and that it is desired to ascertain how far the aeroplane is above the land or sea, the operator fires the gun. The bob is shot downwardly and the cable is unwound from the reel at high speed. On firing the gun the operator watches the odometer and the flashing of the signal permits him to take his reading, and he can then ignore the further action of the device except to load the gun in case a succeeding reading is desired.

It will be appreciated that the movement of the bob out of the path of the finger 44 permits the electromagnet 40 when energized to draw the switch 39 into circuit closing position engaging the contact 41 as hereinafter described.

The movement of the plate 55 into engagement with the ground, sea or other ob-

- ject, will momentarily close the circuit through the conductors 51 and 52, energizing the electromagnet 40 for a period of time sufficient to permit the switch 39 to 5 close and sufficient to cause a flashing of the signal 48. The movement of the switch into engagement with the contact 41 completes the motor circuit and the button 45 acts to hold the switch in its circuit closing position. 10 It will thus be seen that the signal is flashed the instant the bob strikes the obstacle and the motor will promptly begin to wind up the cable onto the reel. This will continue so long as the switch 39 is maintained in circuit closing position. The 15 movement of the bob into its final position in the gun will act through the arm 44 to force the switch 39 into the open position shown in the drawings and the parts are then in 20 position ready to receive a new charge of explosive and to repeat the operation described.

By means of a device of this character it is possible to take rapidly succeeding readings and when once inaugurated each succeeding operation is entirely automatic except for the reloading and firing. It is possible to take rapid soundings while travelling in the dark at high speeds and thus feel 30 the way cautiously over strange territory. There is no loose slack to the cable for the cable begins to re-wind the moment contact is made with the obstacle which might otherwise hold the bob. The bob is not dragged 35 horizontally for any appreciable distance and there is thus eliminated the possibility of catching.

While I have shown and described, and have pointed out in the annexed claims, certain novel features of my invention, it will 40 be understood that various omissions, substitutions and changes in the form and details of the device illustrated and in its operation may be made by those skilled in the art without departing from the spirit of the invention.

Having thus described my invention, I claim:—

1. In a device of the class described, the 50 combination with an aeroplane, of a lead line mechanism mounted on the aeroplane and including a reel, a flexible cable wound on said reel and provided with a bob at its free end, and a gun for projecting the bob 55 with high velocity through the air relatively to the flight of the aeroplane, and drawing the cable off said reel.

2. The combination with an aircraft of a device for measuring distances including a 60 reel having a flexible cable wound thereon, a gun for projecting the bob and cable with high velocity relatively to the flight of the airplane, a motor adapted to be connected to the reel to re-wind the cable thereon, signal- 65 ing means, control means for the motor, cir-

cuit means adapted to be closed upon impact by the bob for operating said two last named means, and means actuatable by the bob on reaching its return position to operate said control means whereby to open the circuit 70 means through the motor.

3. In a device for measuring vertical distances from an aircraft in flight, the combination of a reel having a flexible cable wound thereon, a gun, a projectile for the gun connected to the free end of the cable to constitute a bob, and means for firing the gun whereby to unwind the cable with relatively high velocity from the reel. 75

4. In a device of the class described, the combination of a support including a pair of bearings, a reel including a hub journaled in one of said bearings, a cable wound on said reel and containing an electric conductor, power means operatively connected to 80 said hub to wind the reel in one direction, a hollow shaft carried by the other bearing and constituting a bearing for the other end of the hub, a commutator carried by the hub, a conductor connecting the rotary element of 85 the commutator with the conductor in the cable and another conductor leading through said hollow shaft to make a sliding contact with the commutator. 90

5. The combination with an air craft of a high pressure gun, a cable including a bob on one end thereof constituting a projectile for the gun, a reel for said cable, a motor acting on said reel for placing the bob in its raised position in the gun, and means for cushioning 95 the bob as it is moved into position. 100

6. In a device of the class described, the combination with a gun, of a cable including a bob on one end thereof constituting a projectile for the gun, a reel for said cable, an electric motor acting on said reel for placing the bob in its raised position in the gun, means for cushioning the bob as it is moved into position and a switch operatively controlled by the movement of the bob into its raised position to intercept the action of the 105 motor. 110

7. In a device of the class described, the combination with a gun, of a cable having a bob on one end thereof constituting a projectile for the gun, means for forming an electric circuit including a source of electric energy, a motor in said circuit for elevating the bob, and an electromagnetically controlled switch for completing the circuit, 115 said switch being moved into an open position by the movement of the bob into the gun thereby to intercept the bob lifting movement of the motor. 120

8. In a device of the class described, the combination of a cable having a bob on the free end thereof, a receptacle for containing the bob when in elevating position, an organization of elements for forming an electric circuit, including a motor for elevating the 125 130

bob and two controlling switches arranged to close the circuit through the motor only when both switches are closed, one of said switches having a portion disposed in the path of the bob and adapted to be held in open position by the bob when in said receptacle, magnetic means for closing said switch when free of the bob, the other switch carried by the bob and adapted to be moved into closed position by the contact of the bob with an obstacle.

9. The combination with an aircraft of a lead line having a bob on one end, means for projecting the bob with high velocity relatively to the flight of the air craft, and

means controlled by the engagement of the bob with an obstacle for raising the bob.

10. The combination with an aircraft of a lead line having a bob on one end thereof, means for projecting the bob with high velocity relatively to the flight of the air craft, power means for raising the bob, and means controlled by the respective terminal positions of the bob for starting and stopping the action of said power means.

Signed at New York city, in the county of New York and State of New York, this 10th day of April, A. D. 1920.

HENRY E. KRAMMER.
